SNOW-REMOVAL ATTACHMENT FOR A BROOM

Thomas J. Collings, Railroad Ave.,
Glen Head, N.Y. 11545

Filed Aug. 29, 1967, Ser. No. 8,421

Term of patent 3½ years

(Cl. D4—4)

FIGURE 1 is a perspective view of a snow-removal attachment for a broom embodying my new design,
FIG. 2 is a top plan view thereof.

FIG. 3 is a rear elevational view thereof.

FIG. 4 is a side elevational view thereof.

FIG. 5 is a front perspective view of a modified form of the design shown in FIGS. 1-4.

FIG. 6 is an end elevational view thereof, shown in non-operating position.

FIG. 7 is a top plan thereof.

FIG. 8 is a rear elevational view thereof, and

FIG. 9 is a side elevational view thereof.

The broken line showing of the broom in FIGS. 1, 5 and 6, the handle of which is shown broken away in FIG. 6, is for illustrative purposes only.

I claim:

The ornamental design for a snow-removal attachment for a broom, substantially as shown and described.
